ADJUSTABLE EAR PLUG OR THE LIKE

Frederick C. Visor, Englewood Cliffs, N.J., assignor to Flents Products Co., Inc., New York, N.Y.

Filed May 29, 1973, Ser. No. 364,855

Term of patent 14 years

Int. Cl. D24—04

U.S. Cl. D83—1 J

FIG. 1

FIG. 3

FIG. 1 is an end view of an adjustable ear plug or the like, embodying my design;

FIG. 2 is a side view of the adjustable ear plug or the like of FIG. 1, all side views being identical; and

FIG. 3 is a view of the other end of the adjustable ear plug or the like of FIG. 1.

I claim:

The ornamental design for an adjustable ear plug or the like, as shown.
